Inventor:
E. G. Sherman,
By G. C. Maynard, atty.

UNITED STATES PATENT OFFICE.

EATON G. SHERMAN, OF LOS ANGELES, CALIFORNIA.

KNOCKDOWN SHOE RACK.

Application filed December 30, 1924. Serial No. 758,839.

To all whom it may concern:

Be it known that I, EATON G. SHERMAN, a citizen of the United States, and resident of Los Angeles, State of California, have invented new and useful Improvements in Knockdown Shoe Racks, of which the following is a specification.

This invention relates to an article of household utility and has for an object to provide a very simple, yet substantial shoe rack which may be stocked, stored and shipped in knocked down form, and is easily set up or assembled in useful position of the parts by any person of ordinary intelligence.

An object is to provide a shoe rack of few but firm parts, each designed for economical cost of production and made of stamped sheet metal, producing, when completed, a rack of very durable and at the same time light-weight character.

An object is to provide a rack which may be packed into a shallow carton, to conserve space in storage and shipment, and will require but a moment's time in erection and installation.

Numerous other objects and advantages will be made manifest in the following specification of embodiments of apparatus of the invention illustrated in the accompanying drawing; it being understood that modifications, variations and adaptations may be resorted to within the spirit of the invention, and its scope as here claimed.

Fig. 1 is a perspective of one form of the rack as installed.

Fig. 2 is an end view of the double hook rack frame.

Fig. 3 is a section of bracket having in-struck loops for the double hooks of Fig. 2

Fig. 4 is a detail section showing a slipper supporting horn of a bracket.

Fig. 5 is a perspective showing a form of bracket adapted for reverse use at either end of the rack frame and having interlocking hooks on its front edges.

Fig. 6 shows another form of reversible bracket from the frame.

Fig. 7 is a perspective of a rack having hinged end brackets.

Fig. 8 is a perspective of a hinging bracket.

Fig. 9 is a detail section showing setting up of a bracket.

Fig. 10 is a section showing the set bracket.

One of the features of my invention comprises an elongated frame which, for economy in cost and low weight, I make of an integral stamping of thin sheet metal.

The frame has top and bottom rails 2 an indeterminate connecting means, as a stiffening tie 3, which may be elongated to provide an ample name plate, and the ends of the rails are connected by end stiles 4, all these parts being coplanar.

The rails are provided with repressed, longitudinal embossments 5 which give desired rigidity to the rails and yet leave flat front faces for the hollow of the sole of the shoes to rest solidly on when the breast of the heel of a shoe is hung down on the upper edge of the top rail 2.

The grooves formed by the embossments extend from end to end of the rails so that no unsightly enamel heaps will form when the frame is enamelled.

On each end of the frame is a backturned flange 6 from whose edge 7 extends a pair of similar hooks 8, of undirectional disposition. The throat of each hook has an inclined edge 9 so binding action results when the hooks are applied to respective brackets 10.

Brackets 10 are right and left hand and have front edges inclined upwardly and rearwardly to hold the attached frame in a similar tilt. Along the front edge of each bracket 10 are in-struck loops 11 offset just enough to receive the hooks 8 of the frame 2—2 which pass on the inner side of the brackets. The edge 7 of flange 6 engages the near edges of loops 11 of the respective bracket and forms a positioning gage.

When the hooks 8 pass across the loops the parts 10—2 are then shifted so as to pass a part of each loop 11 up into the convergent throat of its hook. This causes the loop part engaged to bind in the throat and prevent undue play.

The bracket 10 not only supports the rail frame 2 but also forms a support for heelless slippers and the like. To that end each bracket has a horn 12 cut in its web. This horn is left nearly flat with the web when punched so that the brackets can nest or pack close in a carton. The purchaser has but to press in on the horn after the bracket base 13 has been nailed or screwed to a primary support, as a door, panel or wall, at any suitable height. When so installed foot 110

wear having heels can be hung by the placing of the heel against the top rail of the frame.

In so far as foot wear is concerned this utility takes them off the floor.

In Fig. 5 the device includes a bracket 10^a having forwardly convergent front edges 10' meeting on the medial line of the web and having rearwardly pointing hooks 15, the throats of which are designed to snugly receive the inserted ends 4, of the rail frame, which are slotted at 16 to pass over and then pressed down into the hooks. To obtain rigidity, the flange 6 is pressed under a retaining finger 10^c punched laterally from the bracket web.

The bracket 10^a also has a pair of reversely arranged horn parts 12^a with heads aligned between the side edges of the bracket. From this it will be seen that a bracket 10^a is reversible and interchangeable for use at either end of the frame; the fastening base being disposed outwardly so as to facilitate driving of its fastening screw or nail.

Fig. 6 discloses a form of bracket 10 having an inturned flange 17 with a tongue 17^a medially of its length to tightly interlock in a loop 18 struck back in the end stile 4 of the rail frame. The advantage of this form of structure is that the bracket may be made of the punchings cut out of the sheet when making the frame openings between the rails, and at the same time permits the full width of a sheet of stock to be utilized for a maximum length of rail frame without any turned flanges on the ends, which cause a loss of length, when employed.

Figs. 7, 8, 9 and 10 show a form of rack having hinged end brackets.

Each bracket 20 has a front oblique edge 21 marginally deflected at 22 so that the plate of the bracket can be swung out flat against end flanges 6^a which stand back at right angles to the frame 2—2.

The margin 22 is provided with slots 23 to receive lugs 24 on the ends of the frame. These lugs have half-round bends 25 allowing the hinge bars 22^a to roll from the flat

position *a* of the bracket 20 to the upright 50 or set-up position *b*, Fig. 10. When a bracket is swung out to be set up the lug 24 is pressed outward and the edge 21 of the bracket passes over a latching tooth 26, Fig. 10, and is locked by the tooth. 55

The end stile 4 of the device as shown in Fig. 6 has on its inner edge an inturned stiffening flange 4^a. In this form of the rack the frame is made from full width sections cut from a strip of stock, and the brackets 60 are made from the cuttings punched out when the frame is stamped from the stock. To further ensure interlock of the tongue and the frame of the device as shown in Fig. 6, the tongue has a small hole 17^b into 65 which will spring a small depressed bulge 4^b in the inner, marginal portion of the stile 4. This will effectively prevent the members from slipping apart while they are being fastened to a door or other primary support.

What is claimed is:

1. A knock-down shoe rack including a reversible front frame having end stiles, a pair of brackets, each bracket having an 75 oblique front edge to support the stiles, and tongue and loop means whereby the reversible frame may be attached in either position of the frame to the bracket.

2. A knock-down shoe rack including a 80 reversible front frame having upper and lower rails and end stiles having rearwardly embossed loops, and end brackets having oblique front edges provided with laterally 85 bent prongs lying in the plane of the oblique edges to interlock in the loops and hold the parts assembled until fixed to a primary support.

3. A knock-down shoe rack including a front frame having end stiles with depressed loops and depressed bulges contiguous to the loops, and end brackets having tongues to interlock in the loops and having holes to receive the said bulges whereby further interlock is obtained when the 95 tongues are pressed under the bulges.

EATON G. SHERMAN.
